UNITED STATES PATENT OFFICE.

WILLIAM J. MOORE, OF CHICAGO, ILLINOIS, ASSIGNOR OF ONE-HALF TO
CYRUS A. HOUGHTON, OF SAME PLACE.

DETACHABLE BUTTON.

SPECIFICATION forming part of Letters Patent No. 531,466, dated December 25, 1894.

Application filed January 29, 1894. Serial No. 498,346. (No model.)

To all whom it may concern:

Be it known that I, WILLIAM J. MOORE, a citizen of the United States, residing at Chicago, in the county of Cook and State of Illinois, have invented a certain new and useful Improvement in Detachable Buttons, which is fully set forth in the following specification, reference being had to the accompanying drawings, in which—

10 Figure 1, is a top or plan view of my detachable button. Fig. 2, is a vertical, sectional view, taken at the line 2—2, Fig. 1; and Fig. 3, is a horizontal, sectional view, taken at the line 3—3, Fig. 2, looking downward.

15 My invention relates to the class of buttons which can be attached to garments without the use of needle and thread, and can be detached and again attached without injury to the button or the attaching devices.

20 My invention consists in the devices and combination of devices hereinafter fully described and made the subject matter of the claim.

25 In the accompanying drawings, A, represents the under plate of a metallic button to which is a downwardly projecting tube, B, attached, there being an opening through the tube and through the center base-plate A. The tube B serves as a lateral support to 30 the stem of the button when the stem passes through the tube and is locked therein, as hereinafter described.

35 C, is the face-plate of the button which may be stamped in any of the well-known forms for making buttons. The edges of this face-plate C are swaged over the edges of the base-plate A, as clearly shown in Fig. 2; but I do not limit myself to any particular configuration of the face-plate, and it may be connected to the base or bottom-plate of the button in any of the well-known ways of making buttons.

40 D, is a metal spring, which I preferably make of one piece, cut in the form clearly shown in Fig. 3 of the drawings. One end of this spring is provided with a recess or notch E, which fits under the shoulder made on the stem of the button, as clearly shown in Fig. 2. The spring D fits in the space between 45 the front or face-plate C of the button, and the base plate A, and there is attached to this

spring a pin, F, one end of which projects through a slot, G, in the button, where it is accessible to be used to press the spring back, relieving it from under the shoulder in the 55 stem of the button when the stem can be readily removed from the head of the button and from the garment.

H, is the stem of the button, provided with a pointed head I and an annular shoulder, J. 60 This stem is attached to a plate or shoe, K, in any of the well-known methods of attachment for such pieces of metal.

The user of the button first presses the stem H of the button through the cloth of the garment to which the button is to be attached, the pointed head I of this stem making its own hole through the cloth. The tube B is then placed over the pointed head of the button, and by pressing the head of the button 70 down on the stem, this pointed head I forces the one end of the spring D back until it reaches the shoulder of the stem, when the end of the spring passes under this shoulder, the notch E fitting partly around the neck of 75 the stem under the shoulder and locking the stem H of the button to the head of the button. The tube B of the button serves to brace the stem H and keep the button well in place on the garment. 80

When it is desired to remove the button from the garment, a person presses the pin F back in the slot G, throwing the spring D back from under the shoulder J of the stem H when the button-head is readily removed 85 from the stem and the stem from the garment.

It will be observed that my button is cheaply made, consisting of few parts, and can be readily attached to and removed from garments. The spring D is a simple spring, and is held in place between the parts which form the head of the button, fitting against the periphery of the chamber in the head of the button throughout part of its length, but is 90 so constructed that it is thrown forward partially over the opening in the tube B when in its normal position, and the pin F passing through a slot G in the button serves to keep it in place so that the point of the head on 95 the stem of the button will always enter the notch E in the spring when the button is 100

being attached to the garment, and the head will force the spring back until the shoulder on the stem of the button passes the spring, when the tension of the spring throws it forward under the shoulder on the stem of the button.

Having thus fully described the construction and operation of my invention, what I claim, and desire to secure by Letters Patent, 10 is—

In a detachable button, the button-head composed of a face-plate and a back plate, the back or base-plate being provided with a tube for laterally supporting the stem of the 15 button; a spring located in the head of the button, one end projecting over the tube of

the back or base-plate of the head; a pin attached to said spring near its free end and projecting through a slot in the head of the button for throwing the spring back; a button stem rigidly attached to the shoe of the button, and provided with a pointed head which penetrates the cloth, and a recess forming a shoulder at the base of the pointed head under which the spring in the head of 25 the button engages to hold the post in the button-head; and a shoe to which the stem is rigidly attached, as specified.

WILLIAM J. MOORE.
